TRAY

Alvin W. Levenhagen, Ashtabula, Ohio, assignor
to Molded Fiberglass Tray Co., Linesville, Pa.,
a corporation of Pennsylvania

Application June 8, 1953, Serial No. 25,363

Term of patent 7 years

(Cl. D44—10)

To all whom it may concern:

Be it known that I, Alvin W. Levenhagen, a citizen of the United States, residing at Ashtabula, in the county of Ashtabula and State of Ohio, have invented a new, original, and ornamental Design for a Tray, of which the following is a specification, reference being had to the accompanying drawing, forming part thereof.

Figure 1 is a perspective view of a tray, showing my new design;

Figure 2 is an edge view thereof, and

Figures 3 and 4 are cross-sectional details on an enlarged scale, taken substantially in the

planes of the lines 3—3 and 4—4, respectively, in Figure 1.

I claim:

The ornamental design for a tray, as shown.
